UNITED STATES PATENT OFFICE.

JOHN F. O'CONNOR, OF CHICAGO, ILLINOIS, ASSIGNEE TO WILLIAM H. MINER, OF CHICAGO, ILLINOIS.

DRAFT-YOKE FOR RAILWAY-CAR DRAFT-RIGGING.

1,136,036.

Specification of Letters Patent.

Patented Apr. 26, 1915.

Application filed February 24, 1913, Serial No. 750,125. Renewed August 12, 1914. Serial No. 858,491.

To all whom it may concern:

Be it known that I, JOHN F. O'CONNOR, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of this specification.

My invention relates to improvements in draft yokes for railway car draft rigging.

The object of my invention is to provide 15 a draft yoke having provision for maintaining the draft gear therein in central position with reference to the central line of draft of the draft rigging.

My invention is an improvement upon my 20 previous invention upon which a patent was issued November 6, 1906, as No. 835,249.

In the accompanying drawings forming a 25 part of this specification Figure 1 is a side elevation of a railway car draft rigging embodying my invention. Fig. 2 is a plan view. Fig. 3 is a vertical cross section on line 3-3 of Fig. 1.

In the drawings 4 represents draft sills or parts of the car frame to which the draft 30 rigging is attached, 5, 5 front stop members, 6, 6 rear stop members, 7 the front follower, 8 the rear follower, 9 the tie plate suitably secured to the draft sills, 10 the draw bar, 11 the draft gear, 12 the draft 35 yoke, and 13 a coupler key.

The draft yoke 12 consists of a pair of

parallel side extensions of the draw bar or loops 14, 14, extending at their front ends one on either side of the draw bar 10, and connected thereto by the coupler key 13. 40 The loops 14, 14 are each provided with a lateral opening 15, and within the said openings there is received the followers, and between them the draft gear 11. Each of said loops 14, 14 is provided along its outer 45 edges, and preferably the middle portion thereof, with inwardly turned flanges 16, 16, the said flanges having their edges adjacent the draft gear 11 conformed to the shape of the adjacent portions of the draft 50 gear or compression resisting member, as shown at the numerals 17, 17 in Fig. 3 of the drawings. The flanges with which the yoke is thus provided serve to maintain the draft gear in central position with reference to the central line of draft. 55

I claim:

In a draft rigging for railway cars, in combination, a shell, a draw bar, a draft yoke secured to said draw bar, the draft 60 yoke comprising a pair of independent substantially parallel loops, each of said loops being provided at its outer edges with inwardly turned flanges adapted to engage the shell, said flanges being adapted to limit the 65 movement of said loops toward each other through the engagement thereof with the shell.

JOHN F. O'CONNOR.
